Primary Examiner—Robert C. Spangler**Attorney, Agent, or Firm—J. Wesley Blumenshine; John M. Pollaro; Richard C. Witte****[57] CLAIM**

The ornamental design for a bottle, as shown and described.

DESCRIPTION

FIG. 1 is a front elevational view of a bottle embodying my new design;

FIG. 2 is a top plan view thereof;

FIG. 3 is a bottom plan view thereof;

FIG. 4 is a right side elevational view thereof; and

FIG. 5 is a left side elevational view thereof.

The rear elevational view of the bottle is not shown, and is essentially a mirror image of the front shown in FIG. 1.
